UNITED STATES PATENT OFFICE.

CHARLES EDWARD HAVILAND, OF LIMOGES, FRANCE.

DESIGN FOR A COVER-DISH.

SPECIFICATION forming part of Design No. 28,928, dated June 28, 1898.

Application filed June 1, 1898. Serial No. 682,305. Term of patent 7 years.

To all whom it may concern:

Be it known that I, CHARLES EDWARD HAVILAND, a citizen of the United States, residing at the city of Limoges, in the Republic of France, have invented and produced a new and original Design for a Cover-Dish or Similar Article, of which the following is a specification, reference being had to the accompanying drawings, forming part thereof, and in which—

The leading features of my design consist of the ornamental form and configuration of the dish and its cover, substantially as illustrated in the accompanying drawings.

In the drawings, A designates the body of the dish, and B the cover therefor, the said cover having a raised central portion C, bearing a handle D. The rim of the cover B has a scalloped edge and bears the ornamental band comprising the scroll-figures E, the scroll-figures F, which at their center have the appearance of being connected to the scroll-figures E, and the scroll-figures G, which are intermediate the ends of the figures E F.

The sides of the body A of the dish harmonize in outline with the edge outline of the cover B, as denoted in Fig. 2, and said sides extend downward and then turn inward, as shown in Fig. 3, to the base H.

The sides of the body A, adjacent to the horizontal line, at which they turn inward and downward to the base H, bear the ornamental band substantially corresponding with the ornamental band on the rim of the cover B and comprising the figures I J K.

At opposite ends of the body A are handles L L.

What I claim is—

The design for a cover-dish or similar article, substantially as shown and described.

Signed at New York, in the county and State of New York, this 31st day of May, A. D. 1898.

CHARLES EDWARD HAVILAND.
